FREE-TRIPPING OVERLOAD SWITCH

Alvin W. Krieger, Milwaukee, Wis., assignor to
Cutler-Hammer, Inc., Milwaukee, Wis., a corporation of Delaware

Application June 27, 1949, Serial No. 101,601

9 Claims. (Cl. 200—116)

1

This invention relates to free-tripping overload switches, and while not limited thereto, particularly to switches of the character described adapted for use in aircraft of the like wherein a high degree of reliability and high electrical capacity in small sizes are paramount.

A primary object of the invention is to provide a snap acting switch with means for automatically tripping the switch on the occurrence of predetermined overload of high reliability and more particularly to render such automatic tripping free from interference by the normal switch actuating means and without dependence upon any part thereof.

Another object is to provide a switch of the character described which has a high capacity for its size.

Another object is to provide a switch of the character described having adequately powerful tripping means in the event its contacts become welded.

Another object is to provide a switch of the character described wherein the contact opening forces on overload tripping may be varied without interference with the normal operating means provided.

Another object is to provide a switch of the character described which will have a relatively low cost and be easy to assemble and more particularly to provide a switch mechanism affording the desired functions which may be easily and inexpensively assembled into a unitary molded insulating base adapted for simple and expeditious mounting to suitable supporting structure.

Another object is to provide in a switch of the character described, means for indicating a tripped condition of the switch and more particularly to indicate such condition by positive movement and retention of the normal operating means to a predetermined position without dependence upon the normal switch actuating means.

Another object is to provide in a switch of the character described for positive resetting of the tripping mechanism by movement of the normal operating means and more particularly to attain such resetting without dependence upon the snap acting mechanism and while maintaining the switch in open circuit condition.

Another object is to improve the details of construction and the operation of switches of the aforementioned character.

Other objects and advantages of the invention will hereinafter appear.

2

The accompanying drawings illustrate an embodiment of the invention which will now be described, it being understood that the embodiment illustrated is susceptible of modification within the scope of the appended claims.

In the drawings:

Figure 1 is an enlarged top plan view of a switch constructed in accordance with the invention.

10 Fig. 2 is a vertical sectional view, on the line 2—2 of Fig. 1; the full line representation of the switch parts illustrating the open circuit position thereof while the dotted line representation illustrates the position of certain parts in the closed or "on" position of the switch.

Fig. 3 is a side elevational view of the switch, the insulating enclosure being sectioned to expose the switch parts, which are shown in the "tripped" position.

15 Fig. 4 is a top plan view of the switch with the cover plate and associated operating lever removed to expose the remainder of the switch parts.

Fig. 5 is a fragmentary sectional view of a portion of the operating lever.

Referring to the drawings, the reference numeral 10 designates a one-piece molded insulating base having a recess 10^a opening to the upper surface thereof for enclosing and supporting the switch mechanism. A stationary contact 11 of slightly resilient electrically conductive metal is mounted on the bottom wall of said recess 10^a and rigidly and permanently attached to base 10 and a terminal lug 12 of well known form as 20 by rivets 13, which provide electrical conductivity between said stationary contact 11 and said terminal lug 12. A U-shaped contactor 14 best shown in Fig. 3 is provided to cooperate with said stationary contact 11, said contactor 14 being 25 pivotally attached to a rectilinearly movable element 15 as at 14^a.

Element 15 is of an inverted U-shape and is 30 movable rectilinearly within vertical grooves 10^b provided on the inner side walls of base 10, said element 15, as best shown in Fig. 4, being provided with pairs of outwardly extending portions 15^a, one at each corner thereof, for guidance within said grooves 10^b. Element 15 is normally biased 35 downwardly by a relatively heavy helical spring 16, the lower end of which encircles a pin 15^b rigidly attached to and supported by a laterally extending ear 15^c of element 15. The upper end of spring 16 abuts a mounting plate 17 provided to cover the open end of base 10 and preferably 40 rigidly attached thereto as by rivets 17^a.

50 Other objects and advantages of the invention will hereinafter appear.

To normally restrain rectilinearly movable element 15 against the bias of its spring 16, a latching means 18 is provided. Said latching means (Figs. 2 and 3) comprises an upstanding bimetallic element 18^a consisting of two metals having a differential expansion characteristic, and an L-shaped support member 18^b to which said bimetallic element is rigidly and permanently attached to afford a good electrical connection therebetween. The upper end of bimetallic element 18^a is adapted to engage an outwardly extending lug 15^d on element 15 and to restrain the latter against downward movement in response to the bias of its spring 16 as aforescribed.

As best shown in Fig. 3, said supporting member 18^b is rigidly and permanently attached to the bottom wall of recess 10^a and electrically connected to a terminal lug 19 as by rivets 20. Additionally the vertical portion of member 18^b is provided with a laterally extending fin 18^c which, as best shown in Fig. 2, may be engaged by a screw 21 threaded into the horizontal portion of member 18^b for movement of fin 18^c and hence of bimetallic element 18^a for calibration thereof, it being obvious that slight movement of fin 18^c results in relatively greater movement of the upper end of bimetallic element 18^a with reference to lug 15^d.

A pigtail 22 is also provided to afford electrical conductivity between bimetallic element 18^a and rectilinearly movable element 15, it being apparent that upon engagement of contacts 11 and 14 bimetallic element 18^a is connected in series therewith, the current flowing from terminal lug 19, through latching means 18, rectilinearly movable element 15, contactor 14, stationary contact 11, to terminal lug 12.

If a current in excess of that to which bimetallic element 18^a is calibrated should occur, element 18^a will deflect to the right, out of engagement with portion 15^d of rectilinearly movable element 15. The latter will move downwardly in response to the bias of its spring 16 carrying with it the pivoted end of contactor 14. The inner side walls of base 10 are each provided with an inwardly extending integrally formed projection 10^c against which contactor 14 is driven during the aforementioned downward movement of its pivoted end, said projections 10^c affording a fulcrum point for pivotal movement of contactor 14 for disengagement thereof from stationary contact 11 as shown in Fig. 3.

It will be apparent that projections 10^c are so located as to allow rectilinearly movable element 15 and contactor 14 carried by it to pick up considerable momentum before the latter is driven against said projections 10^c thus affording a hammer-like blow should the contacts be frozen or welded. The aforementioned resiliency of stationary contact 11 additionally permits an increment of momentum of the moving parts; the aforescribed arrangement thus affording a high rupturing force for the switch in the event of welding of the contacts on overload. It will also be apparent that such force may be varied by strengthening of spring 16.

It will be noted from the foregoing description that not only is a switch of high rupturing capacity afforded, but also that automatic breaking of the circuit due to tripping on overload is accomplished without dependence upon or interference by any part of the means for normal operation of the switch, to be hereinafter described, thus affording a switch of high reliability and which may be depended upon to function in the emergency for which it is designed regardless of the wear or possible inoperability of the means for effecting normal operation of the switch.

It will further be apparent that the rectilinear movement of certain parts upon the occurrence of an overload not only increases the rupturing capacity of the switch, but also obviates the necessity for pivot pins or the like attached to or extending through the base, thus permitting ease of assembly and use of a unitary molded insulating base, which is less costly than a split base and better adapted to one or three hole mounting or the like required in the application contemplated. Similarly the aforementioned construction provides compactness and strength of the parts to afford a switch of high capacity and relatively small size.

For normal engagement and disengagement of the switch contacts, snap acting operating means are provided comprising a toggle member 23, an operating lever 24 and a helical over-center spring 25. As best shown in Figs. 2 and 4, the toggle member 23 is channel-shaped and has an upwardly extending arm 23^a giving the member the form of an inverted T. A pair of outwardly extending ears 23^b at one end of said member 23 are positioned for pivotal movement in V-shaped notches 26^a (Fig. 2) formed in the side edges of each of the upwardly extending arms of a U-shaped supporting member 26, the latter being rigidly attached to the bottom wall of recess 10^a as by a screw 27. Said member 26 additionally has a pair of horizontally extending arms 26^b which function as a stop to limit upward movement of U-shaped contactor 14 positioned outside of said member 26 as best shown in Figs. 3 and 4. The opposite end of toggle member 23 is provided with a pin 23^c (Fig. 2), over-center spring 25 being connected between said pin and the free end of contactor 14.

The upper end of arm 23^a of toggle member 23 is provided with a pin 28 for slidable linkage of toggle member 23 with a forked insulating portion 24^a of an operating lever 24. Operating lever 24 additionally comprises an external operating portion 24^b of well known form, and a pin 24^c (Figs. 2 and 5) for pivotal attachment of the lever 24 as a whole to a bushing 17^b through which it extends, said bushing being rigidly attached to and extending upwardly from the mounting plate 17. As best shown in Fig. 5, pin 24^c additionally provides a means for holding portions 24^a and 24^b in the desired relationship, portion 24^a having a hole at the upper end through which pin 24^c extends. Insulating portion 24^a blocks electrical conductivity from the switch parts to the external portion 24^b of operating lever 24 and to mounting plate 17, the latter being additionally insulated from current carrying parts by an insulating gasket 33 and a cup-shaped member 34 of insulating material (Fig. 3) interposed between spring 16 and said mounting plate.

As will be apparent, movement of operating lever 24 to or from one of its extreme positions as illustrated in Fig. 2 by the full line and dotted line representations respectively, is transmitted through toggle member 23 to contactor 14 by way of over-center spring 25. As will be obvious to those skilled in the art, clockwise movement of toggle member 23 about its pivot 26^a from the full line representation illustrated, will cause spring 25 to pass through center and result in

engagement of contactor 14 with stationary contact 11, while counter-clockwise movement of toggle member 23 from the dotted line representation of Fig. 2 will similarly result in disengagement of the contacts with a snap action while the switch mechanism is latched as previously described.

In the event that the switch is tripped by an overload and the circuit opened as hereinbefore described, the switch parts will take the positions shown in Fig. 3. It will be apparent that in this position clockwise movement of toggle member 23 about its pivot at 26^a by movement of operating lever 24 to the left or "on" position, cannot result in closing of the switch contacts since in the tripped condition downward movement of rectilinearly movable element 15 has carried the pivoted end of contactor 14 downwardly a corresponding distance and projections 10^c of base 10 block movement of contactor 14 to the closed circuit position, thus rendering the switch mechanism trip-free. Should it be attempted to reset the tripping mechanism and to close the switch contacts while the overload persists, latching means 18 would again allow the switch to trip open regardless of whether or not operating lever 24 were held in the "on" position.

It will be further noted that upon tripping of the switch by downward movement of element 15, the tension of over-center spring 25 is lessened sufficiently to permit a relatively light helical spring 29 connected between pin 28 on toggle member 23 and a lug 26^d provided therefore on one of the horizontally extending arm 26^c of member 26 to carry toggle member 23 in a counter-clockwise direction, which movement, however, is limited by a stop afforded by engagement of an extension 23^d on one end of said member 23 with element 15 now in its downwardly biased position. The parts are so proportioned as to limit the aforementioned movement of toggle member 23 to carry operating lever 24 to a position intermediate its extreme operating positions and for retention there to indicate the tripped condition of the switch. Thus it will be apparent that provision is made for positive indication of such tripped condition of the switch without dependence upon the operation of over-center spring 25, thereby insuring reliable indication of the condition of the switch.

The aforementioned engagement of portion 23^d of toggle member 23 with element 15 in its downwardly biased position, additionally constitutes a means for relatching of the latching means 18 inasmuch as movement of lever 24 to the "off" position results in counter-clockwise movement of toggle member 23 against element 15 and its biasing spring 16, thus tending to raise element 15 to a point where bimetallic element 18^a may again engage the underside of lug 15^d of element 15. As will be apparent, the aforescribed resetting is accomplished without dependence on over-center spring 25 and since resetting is afforded by movement of operating lever 24 to the "off" position, such resetting is accomplished while the switch contacts are maintained open. The circuit may then be closed by movement of operating lever 24 to the closed or "on" position through the normal snap acting means hereinbefore described.

The switches illustrated in the drawings, additionally show a dust boot assembly of the type disclosed in my copending application, Ser. No.

64,077, comprising a dust boot 30 and a member 31 for clamping the boot 30 to base 10 to overlie mounting plate 17, the latter also having a pair of self-locking nuts 32 (Fig. 2) of well known type for mounting of the switch to suitable supporting structure.

I claim:

1. A free-tripping overload switch comprising, in combination, a rectilinearly movable element 10 biased in one direction, cooperating contacts including a contactor pivotally supported on said element, thermally responsive latching means restraining said element against its bias, to release said element upon the occurrence of an overload, operating means for said contactor to engage and disengage said contacts at will while said element is latched and to relatch said element while maintaining said contacts disengaged, and a fixed part against which said element when released, drives said contactor for pivotal movement of the latter for disengagement of said contacts free from interference by said operating means.

2. A free-tripping overload switch comprising, in combination, a rectilinearly movable element 25 biased in one direction, cooperating contacts including a contactor pivotally supported on said element, thermally responsive latching means restraining said element against its bias, to release said element upon the occurrence of an overload, snap action operating means for said contactor to engage and disengage said contacts at will while said element is latched and to relatch said element while maintaining said contacts disengaged, and a fixed part against which said element when released, drives said contactor for pivotal movement of the latter for disengagement of said contacts free from interference by said operating means.

3. A free-tripping overload switch comprising, in combination, a rectilinearly movable element 30 biased in one direction, cooperating contacts including a contactor pivotally supported on said element, thermally responsive latching means restraining said element against its bias, to release said element upon occurrence of an overload, operating means for said contactor to engage and disengage said contacts at will while said element is latched and to relatch said element when released, said operating means comprising a member movable to one position for engagement of said contacts and to another position for disengagement of said contacts and relatching said element, a fixed part against which said element when released drives said contactor for pivotal movement of the latter for disengagement of said contacts, said operating means being non-interfering with contact disengagement by the last mentioned movement of said contactor but being responsive thereto for movement of said member to an intermediate position.

4. A free-tripping overload switch comprising, in combination, a rectilinearly movable element 65 biased in one direction, cooperating contacts including a contactor pivotally supported on said element and a resiliently mounted stationary contact, thermally responsive bimetal latching means restraining said element against its bias, to release said element upon the occurrence of an overload, snap action operating means for said contactor to engage and disengage said contacts at will while said element is latched and to relatch said element while maintaining said contacts disengaged, and a fixed part against which

said element when released drives said contactor for pivotal movement of the latter for positive disengagement of said contacts without dependence on said operating means.

5. A free-tripping overload switch comprising, in combination, a rectilinearly movable element having a normal fixed position, cooperating contacts including a contactor pivotally supported by said element, operating means for said contactor to engage and disengage said contactor at will while said element occupies said normal position, an overload responsive thermal latch restraining said element in said normal position, means to effect independently of said operating means and free from interference therewith movement of said element and resulting disengagement of said contacts when said latch frees said element, and interconnections between the first mentioned means and said element providing for resetting of the latter by movement of a part of the former to contact disengaging position and for defining an indicating position of such part upon disengagement of said contacts as the result of movement of said rectilinearly movable element upon overload.

6. A free-tripping overload switch comprising, in combination, a rectilinearly movable element biased in one direction, cooperating contacts including a contactor pivotally supported on said element, an enclosure for said switch guiding said rectilinearly movable element, thermally responsive latching means restraining said element against its bias, to release said element upon the occurrence of an overload, operating means for said contactor to engage and disengage said contacts at will while said element is latched and to relatch said element when released, said enclosure having a fixed part against which said element when released drives said contactor for pivotal movement of the latter for disengagement of said contacts independently of said operating means, the latter being responsive to said last mentioned movement of said contactor for movement to an intermediate position indicating a tripped condition of the switch.

7. A free-tripping overload switch comprising, in combination a reciprocal element biased in one direction, cooperating contacts including a contactor pivotally supported on said element, thermally responsive bimetal latching means restraining said element against its bias, to release said element upon the occurrence of an overload, operating means for said contactor including an over-center spring to engage and disengage said contacts at will with a snap action while said element is latched, a fixed part against which said element when released drives said contactor for pivotal movement of the latter for positive disengagement of said contacts independently of said operating means, the latter being responsive to said movement of said contactor for movement of said operating means to an intermediate

position and into engagement with said element, which affords a stop for said operating means for indicating a tripped condition of the switch and for relatching of said element.

8. A free-tripping overload switch comprising, in combination, a rectilinearly movable element, means biasing said element in one direction, cooperating contacts including a contactor pivotally supported on said element, thermally responsive latching means restraining said element against its bias, to release said element upon occurrence of an overload, operating means for said contactor including an over-center spring to engage and disengage said contacts at will with a snap action while said element is latched and to relatch said element when released, and a fixed part against which said element when released drives said contactor for pivotal movement of the latter for disengagement of said contacts, said operating means being non-interfering with contact disengagement by the last mentioned movement and said disengagement being effected by response of said element to its said biasing means and without dependence on said over-center spring.

9. A free-tripping overload switch comprising, in combination, a rectilinearly movable element biased in one direction, cooperating contacts including a contactor pivotally supported on said element, a one-piece insulating enclosure for said switch having grooves to guide said movable element, thermally responsive latching means restraining said element against its bias to release said element upon the occurrence of an overload, and snap acting operating means for said contactor including an over-center spring and a member movable to one position for engagement of said contacts and to another position for disengagement of said contacts and relatching of said element without dependence on said over-center spring, said insulating enclosure having an integrally formed fixed part against which said element when released drives said contactor for pivotal movement of the latter for positive disengagement of said contacts without dependence on said over-center spring, and said operating means being non-interfering with contact disengagement by the last mentioned movement of said contactor but being responsive thereto for movement of its said member to an intermediate position and into engagement with said element.
